JOHN ALFRED BURLANDO, OF NEW YORK, N. Y., ASSIGNOR OF ONE-HALF TO DANIEL M. CASH, OF NEW YORK, N. Y.

COMB AND BARRETTE

1,052,310.

Specification of Letters Patent. Patented Feb. 4, 1913.

Application filed August 30, 1912. Serial No. 717,893.

To all whom it may concern:

Be it known that I, JOHN ALFRED BURLANDO, a citizen of the United States, and a resident of the city of New York, borough 5 of the Bronx, in the county and State of New York, have invented a new and Improved Comb and Barrette, of which the following is a full, clear, and exact description.

10 This invention relates generally to articles for women's wear, and is particularly directed to a new and improved comb and barrette.

15 The principal object of the invention is to provide a coöperating comb and barrette, the barrette being adapted to be held on the comb after the comb has been positioned on the head.

20 A further object of the invention is the provision of a simple structure comprising a coöperating comb and barrette, the use of which prevents loss of the barrette or the comb since the parts are held in engagement with each other and also with the person's hair.

25 Reference is to be had to the accompanying drawings forming a part of this specification, in which like characters of reference indicate corresponding parts in all the views, and in which—

Figure 1 is a side view of the combined structure; Fig. 2 is a side view of the barrette; Fig. 3 is a partial view of the comb having the keyhole slot formed in each of 35 the end teeth; Fig. 4 is a sectional view showing the inter-engagement between the comb and the barrette; while Fig. 5 is a partial view of the rear of the barrette, showing the lug adapted to enter the said keyhole slot.

40 The comb 1 is of conventional form, in that it comprises a number of teeth 2 and a top portion 3 from which the teeth extend, the material of which the comb is made being of no consequence, and the size and shape being capable of variation.

45 The end teeth 2^a of the comb are relatively longer than the intermediate teeth and adjacent their lower ends are provided 50 with keyhole slots 4, as shown particularly in Fig. 3; the particular size and form of

these slots, as well as the relative location on the said end teeth, may, of course, be changed.

55 The barrette 5, as shown, comprises a hollow rectangular structure, such particular form of barrette, however being merely shown to illustrate the inventive idea, since it is apparent that the barrette need not be hollow and need not be rectangular, but 60 may follow any of the conventional styles or patterns, provided with suitable ornamentation. At any event, opposite ends of the barrette are provided with lugs 6, which lugs are provided with headed pins 7, adapted 65 to be positioned in the said keyhole slots, the parts being fixed by giving a slight downward movement of the barrette relatively to the comb in order to bring the head of the pin into engagement with the 70 side of the end teeth 2^a.

The article is positioned in use in the following manner: The comb is placed in position in the hair where desired, and the barrette is then engaged with the comb by 75 bringing about the coöperation between the keyhole slots and pins 7; in such relation the barrette is held against displacement relatively to the comb and the comb and barrette together are prevented from loss 80 by being engaged in the hair. The relative disposition of the comb and barrette is angular to conform to the rotundity of the wearer's head.

Having thus described my invention, what 85 I claim as new and desire to secure by Letters Patent is:—

A structure of the class described, comprising a comb having the ends at the lower portions thereof provided with slots, and a 90 barrette, opposite ends of the barrette being provided with lugs, the lugs being provided with headed pins, the said pins engaging in the said slots, whereby the comb and barrette are held together.

95 In testimony whereof I have signed my name to this specification in the presence of two subscribing witnesses.

JOHN ALFRED BURLANDO.
